UNITED STATES PATENT OFFICE.

GEORGE WEBSTER COULTAS, OF CALAIS, OHIO.

BRIDGE.

SPECIFICATION forming part of Letters Patent No. 365,970, dated July 5, 1887.

Application filed April 4, 1887. Serial No. 233,598. (No model.)

To all whom it may concern:

Be it known that I, GEORGE WEBSTER COULTAS, of Calais, in the county of Monroe and State of Ohio, have invented a new and Improved Bridge, of which the following is a full, clear, and exact description.

The object of my invention is to provide a new and improved bridge which is simple and durable in construction and specially adapted to short-span country bridges.

The invention consists in the construction and arrangement of various parts and details and combinations of the same, as will be hereinafter fully described, and then pointed out in the claims.

Reference is to be had to the accompanying drawings, forming part of this specification, in which similar letters of reference indicate corresponding parts in both the figures.

Figure 1 is a side elevation of my improvement, with parts in section; and Fig. 2 is a vertical cross-section of the same on the lines *xx* of Fig. 1.

The abutment cross-beams A A support the longitudinal single-span beams B, on which are fastened the planks C, in the usual manner.

In the middle of the span-beams B, on the under side, is placed the cross-beam D, clipped on each side by the clip E to a bolt, F, passing transversely through the lower end of the upright beam G, resting on the said cross-beam D, and connected at its upper end with the top rail, H, supported at each end by the end uprights, I I, secured to and resting on the abutment-beams A A. Each bolt F passes through a recess, G', in the beam G, and on each bolt F is pivotally held one end of the four diagonal braces J, which extend upward in pairs in opposite directions to each other and pass through the ends of the top rails, H, and are held in place by the plates and nuts K, screwing against the ends of the said top rails, H.

The braces J support the upright beams G and the cross-beam D, thus forming a very strong support for the span-beams B B. The 45 beams are preferably of wood, while the bolts F, the braces J, clips E, and washer and nuts K are metallic.

Having thus fully described my invention, I claim as new and desire to secure by Letters 50 Patent—

1. In a bridge, the combination, with the span-beams B, the end beams, I, and the top rails, H, of the cross-beam D, the center uprights, G, each having a recess, G', the bolts F, 55 held in the said uprights G, the clips E, for fastening the said cross-beam D to the said bolts F, and the braces J, pivotally connected with one end to the said bolts F, and with their other ends fastened to the outer ends of the top rails, 60 H, substantially as shown and described.

2. In a bridge, the abutment cross-beams A, the span-beams B, supported by the said abutment-beams A and carrying the planks C, the end uprights, I, and the top rails, H, supported 65 by the said end uprights, I, in combination with the center cross-beam, D, the center uprights, G, resting on the said cross-beams D and abutting against the top rails, H, the bolts F, held in the lower ends of the said uprights G and passing through a recess, G', formed in the said uprights G, the clips E, held on the said bolts F and supporting the said center cross-beam, D, the braces J, each connected with one end to the said bolts F, and the plates and nuts K, for 70 fastening the said braces J to the top rails, H, substantially as shown and described.

GEORGE WEBSTER COULTAS.
